UNITED STATES PATENT OFFICE.

ALFRED L. MOORE, OF MOLINE, ILLINOIS.

WAGON.

No. 835,454.

Specification of Letters Patent.

Patented Nov. 6, 1906.

Application filed September 5, 1905. Serial No. 276,927.

To all whom it may concern:

Be it known that I, ALFRED L. MOORE, a citizen of the United States, residing at Moline, in the county of Rock Island and State 5 of Illinois, have invented certain new and useful Improvements in Wagons, of which the following is a specification.

My invention relates to that class of wagons having a front bolster provided with a 10 king-bolt for connecting it with the axle and having an axle provided with a bolster-supporting member—such as a sand-board or lower bolster—upon which the top bolster is mounted.

15 The principal object of my invention is to provide a simple, economical, and efficient means for connecting the bolster or bolsters of a wagon with the sand-board or lower bolster, and thereby with the axle or axles.

20 Other and further objects of the invention will appear from an examination of the drawings and the following description and claim.

The invention consists in the features, combinations, and details of construction 25 hereinafter described and claimed.

In the accompanying drawings, Figure 1 is an end elevation, partly in section, of the front portion of a wagon provided with my improvements; Fig. 2, an enlarged detail 30 view of the upper collar for the king-bolt; Fig. 3, a plan view of the same; Fig. 4, an enlarged detail view in central sectional elevation of the connecting bearing sleeve or collar which connects the top bolster and its 35 bolster-plate with the lower bolster or sand-board and its bolster-plate and forms a bearing for the king-bolt and for such bolster-plates; and Fig. 5, a plan view of the sleeve or collar shown in Fig. 4.

40 In constructing an axle and bolster and bolster-supporting means in accordance with my improvements I provide an axle *a*, upon which is mounted a bolster-supporting member *b* in the form of a lower bolster or sand-board, which is connected to the axle by 45 means of bolts *c*, *d*, *e*, and *f*, which bolts also pass through the interposed frame members *g* and *h*. A lower bolster-plate *i* is mounted on the bolster-supporting member or sand-board *b* and provided with a central perforation 50 for receiving the king-bolt and bearing sleeve or collar hereinafter described. A top bolster *j* is mounted upon and supported

by such bolster-supporting member or sand-board and provided with a top bolster-plate *k*, which rests upon the lower bolster-plate *i* and is provided with a perforation which registers with the central perforation in the lower bolster-plate. This upper bolster-plate is secured to the bottom side of the upper bolster by means of bolts *l*, having heads on their lower ends which are countersunk into the bolster-plate and similar heads on their upper ends which are countersunk into the bolster top plate *m*.

55 A connecting and bearing sleeve or collar *n* is mounted with its lower end countersunk into the bolster-supporting member or sand-board *b* and its upper end extending through perforations in the upper and lower bolster-plates and into the upper bolster, so as to 60 permit the upper bolster and bolster-plate to rotate upon such sleeve. The lower end of this bearing-sleeve is provided with an enlarged annular shoulder portion *o* and laterally-extending lips *p*. This enlarged annular bottom portion of the sleeve extends 65 into a countersink in the sand-board, and the lips are depressed into the body portion of the sand-board. The upper surfaces of the annular enlarged shoulder portion of the sleeve and of the laterally-projecting lips are thus engaged by the bottom bolster-plate, and the sleeve is held firmly in place by means of such 70 bolster-plate. The relatively small annular upper portion of the sleeve extends, as already suggested, through the perforations 75 in the upper and lower bolster-plates and into the body portion of the upper bolster, and a king-bolt *q* extends through the axial 80 perforation in such sleeve and through vertical central perforations in the upper bolster, the lower bolster, or sand-board portion, and the axle.

85 An upper metallic bearing collar or sleeve *r* is provided with laterally-extending lips *s* and mounted in a countersink in the upper surface portion of the top bolster. A tapered countersunk portion *t* and central perforation *u* admit and engage the king-bolt, 90 which is provided with a tapered head *v*. A top plate *m* is provided with a perforation through which the king-bolt extends, the edges or walls of such perforated portion being bent downward or countersunk to 95 correspond to the pitch of the tapered head of 100 105

the king-bolt, so that the collar is securely held in place by the top bolster-plate and the head of the bolt is in engagement with the collar and with the inwardly-bent portions of such plate.

By the above arrangement it will be seen that the lower bearing-sleeve *n* forms a bearing or pivot for the upper and lower bolster-plates and is held firmly in position by the lower bolster-plate and that such sleeve also forms a long bearing for the king-bolt and is adapted to prevent the king-bolt from coming into engagement with the upper and lower bolster-plates, so that all tendency to shear the king-bolt is practically removed. It will also be seen that the upper collar prevents the upper portion of the king-bolt from wearing away the upper bolster and that the king-bolt is prevented from becoming loosened by wearing away either the upper bolster or the lower bolster or sand-board member. The collars are both firmly held in place, the lower one by the lower bolster-plate and the upper one by the bolster top plate *m*. The top bolster and its bolster-plate are prevented from having any undesirable play with relation to the lower bolster-plate, and all of the parts are prevented from being worn away by the king-bolt or by frictional contact with each other, such as would occur if the

connections were allowed to become loosened by wear.

I claim—

In a wagon, the combination of a bolster provided with a perforation for receiving a king-bolt, a king-bolt mounted in such perforation, an axle provided with a bolster-supporting member having a perforation into which the king-bolt extends, upper and lower metallic bolster-plates interposed between such bolster-supporting member and the lower side of the bolster, a bearing-sleeve provided with an enlarged lower end portion extending into the bolster-supporting member and in engagement with the under side of the lower bolster-plate, means for securing such lower bolster-plate and thereby rigidly securing the bearing-sleeve in position, the upper bolster-plate being secured to the upper bolster and provided with a perforation into which the upper end of such bearing-sleeve extends, a metallic collar encircling the upper end of the king-bolt, and a bolster top plate extending over such collar and provided with a perforation for receiving the king-bolt.

ALFRED L. MOORE.
